UNITED STATES PATENT OFFICE.

BERNHARD GREBE, OF DRESDEN, GERMANY.

POST-CARD AUTOMAT.

1,261,381.

Specification of Letters Patent.

Patented Apr. 2, 1918.

Application filed October 24, 1916. Serial No. 127,453.

To all whom it may concern:

Be it known that I, BERNHARD GREBE, a subject of the Emperor of Germany, and a resident of Dresden, Germany, Elisenstrasse 72, have invented certain new and useful Improvements in Post-Card Automats, of which the following is a specification.

The subject matter of the present invention is a postcard automat allowing the choice of the salable cards by means of a window within the casing of the automat.

In the heretofore known automats of this kind the salable cards were arranged in special card-holders or the like disposed one above the other and being moved by means of levers or the like.

The present invention now consists in the cards being loosely arranged in the form of a pile within a special compartment of the automat wherefrom they are brought within the sight of the buyer and returned to said pile if the buyer wishes to see another card; finally the chosen card may be removed from the automat by means of a guide-bar.

In the annexed drawings the subject matter of the present application is represented by way of example in two forms of execution, and therein—

30 Figure 1 represents the automat with a postcard to be seen in the window of the casing.

Fig. 2 shows the automat in section.

Fig. 3 represents the automat in working position.

Fig. 4 shows the pile of postcards, one card being halfway lifted.

Fig. 5 shows a modified form of the device in which the cards after exhibition are returned to another pile.

Fig. 6 shows the cam and rack mechanism for delivering a card, and,

Fig. 7 shows in detail the transport roller, and link used in the form shown in Fig. 5.

45 In the drawings 1 is the receptacle for the postcards 2 which abut with their upper edges against the rollers 3 and 60, which latter simultaneously serve as guide-rollers. 4 is a roller mounted on springs and 5 is a rotatable roller.

50 6, 7, 8 and 9 are likewise rollers. 10 is a support for the postcards when exhibited, 11 the compartment of exhibition within the automat; 12 is a guide rotatable about 13.

55 14 is the slot for the deliverance of the sold postcard, 15 the channel for the coin

16 which will be caught and retained by the nose 17 of the arm 18 which is rotatable about point 19.

20 is a movable guide connected to guide 12. 21 is the lower end of the coin channel 15. 22 is the receptacle for the coins, 23 a guide and 24 a lever with a nose 33 which lever is rotatable about 25. 26 is a slot provided in the lever 24, and in said slot 65 moves the pin 27 provided on arm 18. 28 is a wheel having teeth only on a part of its circumference.

29 is a lever swinging about 30 and having a nose 31 which projects into the channel 15 for the coins. The lever abuts with its lower end 32 against the guide 23 which is fixed to the wheel 28. 34 is a toothed wheel.

35 The roller 3 is connected to the drive-wheel 61 by a fast coupling and the roller 60 in the same way to the drive wheel 62 and the roller 5 to the drive wheel 63. In order to maintain all these three rollers in the same speed of rotation the wheels 64 and 80 75 65 are interposed. The drive wheel 63 is fixed on the roller 5 near the toothed wheel 34. Opposite the roller 5 a stripper 66 is arranged which is adjustable by means of the lever 67.

85 In the second form of execution 35 is a roller provided with rubber tongues 36, 37, 38, 39 and 40 are guide-rollers, 41 is the exhibition compartment, 42 a roller with a tongue 43. 44 is a roller with a groove 45. 90 46 is a link oscillating about point 47 and provided with noses 48 and 49, which knock against flaps 50 and 51.

95 52 and 53 are the compartments for the postcards. 54 is a chain for connecting the rollers 42 and 40. 55 is a rack-mechanism. 56 the channel for the coin.

The mode of operation of the form of execution according to Figs. 1 to 4 is as follows:

The toothed wheel 28 and the toothed 100 wheel 34 are normally out of connection.

By means of a crank handle the roller 5 will be rotated and therewith the drive-wheel 63 and the toothed wheel 34. By means of the interposed wheels 64 and 65 the wheels 105 62 and 61 are moved by the drive wheel 63 and hereby the rollers 60 and 3 will be set in motion as they are rigidly connected to the pinions 62 and 61.

110 The direction of rotation of the rollers is such that the card grasped by the rollers is bound to move upward. Now the rollers 3

and 60 move the card against the roller 4 which is mounted on springs in order to conform to the thickness of the card. The card then passes between roller 5 and strip 5 per 66 and is brought into the exhibition compartment. As soon as the lower edge of the card leaves the rollers 6 and 7 the card lies against roller 9 and falls on account of the overweight at the upper edge back- 10 wardly against the support 10. The lower edge of the card now lies between rollers 6 and 8. In further moving the crank the card passes between the rollers 6 and 8 and falls over guide 12 into the compartment 15 from which it was taken in order to be exhibited.

The rollers 6 and 8 are in fast connection with the drive wheels 68 and 69 which obtain their movement of rotation from the 20 pinion 34.

If one desires to buy a card being exposed in the compartment of exhibition, a coin is to be pressed into the slot 15^a whereby the nose 31 of lever 29 is pressed out of the channel 15. Hereby the lower end 32 of lever 29 acts against the guide 23 which is in fast connection with the wheel 28 and moves the same until its teeth engage the toothed wheel 34. Upon further rotation of the wheel 34 30 the toothed wheel 28 will be rotated, and by means of the guide 23 the lever 24 is pressed downward.

Meanwhile the coin 16 has reached nose 17 and is retained thereby. By depressing the 35 lever 24 the latter moves around point 25 and its upper end moves by means of its slot 26 the pin 27 of the arm 18 in forward direction. Hereby the nose 17 presses the coin 16 against the guide 20 and moves this latter in a forward direction. As the guide 20 40 is connected with the guide 12, the latter will necessarily move around point 13 and takes up such a position as to allow the post card moving downward, to leave the automat 45 through the opening 14.

During further rotation the toothed wheel 28 is rotated, the guide 23 pushes the nose 33 of the lever 24 and presses the upper part of lever 24 backwardly. Hereby arm 18 is also 50 pushed in backward direction, so that nose 17 will release the coin, so that the latter drops into the receptacle 22.

The mode of operation of the form of execution according to Figs. 5 to 7 is as follows:

By rotating the roller 35 the lowermost postcard is brought out of the compartment 52 by means of the rubber tongue 36 and moved upward, passing between rollers 37 60 and 38. During the further rotation of the roller 38 the lower edge of the card enters between rollers 38 and 39 and is brought into the compartment 53. In order to secure the transport of the card into said compartment roller 44 will be rotated. The groove 65

45 of the same then seizes the point of the triangular link 46 and oscillates the same in one or the other direction as may be necessary, so that nose 48 or 49 pushes the flap 50 or 51 backward, whereby the card drops 70 down without any difficulty.

If a card is to be delivered from the automat a coin is brought into the channel 56. This coin releases the rack-mechanism 55, whereafter the wheel 42 is actuated by the 75 drive-chain 54 and the tongue 43 will push the card through slot 57 out of the automat.

As the whole mechanism is very small and room is still left within the apparatus an 80 automat for cigarettes or chocolates may be provided in the same.

The rollers serving to move the postcards to the exhibition compartments may be covered with rubber or the like. 85

It is evident that the described automat may not only be used for postcards but also for, for instance insurance-policies, books and all kinds of articles which one may wish to sell by means of automats. 90

I claim:—

1. Postcard automat comprising a casing, a compartment within the casing for the postcards to be sold, another compartment for exhibiting the salable postcards, means 95 for moving said postcards one after the other into the compartment for exhibition, a delivering slot for the postcard, means for receiving a coin, a receptacle for gathering the coins and means adapted to be operated by said coin for delivering a postcard through said delivering slot as soon as a coin is inserted into the automat. 100

2. Postcard automat comprising a casing, a compartment within the casing for the postcards to be sold, another compartment for exhibiting the salable postcards, a support for the postcard in said compartment of exhibition, rollers against which the upper end of the postcards abut and which simultaneously serve as guide-rollers for the postcards, a plurality of rollers moving the postcards one by one onto the said support within the compartment for exhibition, a delivering slot for the postcards, means for receiving a coin, a receptacle for gathering the coins and means adapted to be operated by said coin for delivering a postcard through said delivering slot as soon as a coin is inserted into the automat. 110

3. Postcard automat comprising a casing, a compartment within the casing for the postcards to be sold, another compartment for exhibiting the salable postcards, a support for the postcard in said compartment of exhibition, rollers against which the upper ends of the postcards abut and which simultaneously serve as guide-rollers for the postcards, a roller mounted on springs, and a rotatable roller as well as a plurality of 120

rollers which move the postcard to the said support within the compartment for exhibition, a delivering slot for the postcards, means for receiving a coin, a receptacle for gathering the coins and means adapted to be operated by said coin for delivering a postcard through said delivering slot as soon as a coin is inserted into the automat.

4. Postcard automat comprising a casing, 10 a compartment within the casing for the postcards to be sold, another compartment for exhibiting the salable postcards, a support for the postcards in said compartment of exhibition, rollers against which the 15 upper ends of the postcards abut and which simultaneously serve as guide-rollers for the postcards, a roller mounted on springs, a stripper and a rotatable roller as well as a plurality of rollers which move the post- 20 card to the said support within the compartment for exhibition, a delivering slot for the postcards, means for receiving a coin, a receptacle for gathering the coins and means adapted to be operated by said 25 coin for delivering a postcard through said delivering slot as soon as a coin is inserted into the automat.

5. Postcard automat comprising a casing, a compartment within the casing for the postcards to be sold, another compartment 30 for exhibiting the salable postcards, a support for the postcards in said compartment of exhibition, rollers against which the upper ends of the postcards abut and which simultaneously serve as guide-rollers for the 35 postcards, a roller mounted on springs, a stripper, a lever connected to said stripper for adjusting the same, a rotatable roller and a plurality of rollers which move the postcards to the said support within the compartment of exhibition, a delivering slot for the postcards, means for receiving a coin, a receptacle for gathering the coins and means adapted to be operated by said coin for delivering a postcard through said 40 delivering slot as soon as a coin is inserted into the automat.

Signed at Dresden, Saxony, this 18th day of August, 1916.

BERNHARD GREBE.
